Specification for Design.

Patented Nov. 4, 1919.

Application filed April 28, 1919. Serial No. 293,360. Term of patent 14 years.

To all whom it may concern:

Be it known that I, JOHN R. SEARIGHT, a citizen of the United States, residing at Detroit, in the county of Wayne and State of Michigan, have invented a new, original, and ornamental Design for a Toy Gun, of which the following is a specification, reference being had to the accompanying drawing, forming part thereof.

Figure 1 is an elevation of one side of the toy gun.

Fig. 2 is an elevation of the other side of the toy gun.

Fig. 3 is a top elevation of the toy gun showing my new design.

I claim:

The ornamental design for a toy gun, as shown.

JOHN R. SEARIGHT.
